UNITED STATES PATENT OFFICE.

ANDREW J. QUIST AND BERT A. MELLANDER, OF MOUNT JEWETT, PENNSYLVANIA.

SHOE STRETCHER.

Application filed December 10, 1925. Serial No. 74,563.

This invention aims to provide novel means for expanding the toe sections of a shoe-tree to effect a stretching of the shoe.

Another object of the invention is to provide novel means for connecting the heel with the toe sections.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the drawings:—

Figure 1 shows in longitudinal section, a device constructed in accordance with the invention, parts being broken away; and Figure 2 is a top plan wherein parts are in section, parts being broken away.

The device forming the subject matter of this application comprises a toe 1. The toe 1 embodies laterally separable sections 2. The sections 2 have inclined longitudinal grooves 3 on their inner surfaces, the grooves defining a guideway 4. The guideway 4 is reduced laterally, as shown at 5 in Figure 2. There are lateral openings 6 in the toe sections 2 near to the rear ends thereof. The openings 6 communicate with the grooves 3. In their upper surfaces, and upon their inner surfaces, the toe sections 2 have cooperating notches 26. Near to their rear ends, the toe sections 2 are supplied with a transverse bore 7. The bore 7 has enlargements 8 at its outer ends. The enlargements 8 form shoulders 9. A connecting element 10, such as a bolt, is located in the bore 7. Nuts 11 are threaded on the bolt 10 and may be spaced at any desired distance from the shoulders 9, the bolt being threaded as at 12, to cooperate with the nuts 11. In their rear surfaces, the toe sections 2 have cooperating notches 14. The toe sections 2 are supplied with a transverse bore 15 located to the rear of the bore 7. The bore 15 has enlargements 16 at its outer ends. The enlargements 16 form shoulders 17. A connecting element 18, such as a bolt, is mounted in the bore 15.

Nuts 19 are threaded at 20 on the bolt 18 and are spaced at any desired distance from the shoulders 17. The nuts 19 and 11 may be adjusted as desired, to limit the amount that the toe sections 2 are separated, by an instrumentality to be described hereinafter. In the inner surfaces of the toe sections 2, near to the rear lower corners thereof, there are oppositely disposed seats 21 receiving a compression spring 22, which tends to swing the toe sections 2 apart, into engagement with the nuts 11 and 19.

The means for expanding the toe sections 2 embodies a tubular nut 23 mounted in the guideway 4 which is formed by the grooves 70 3. The nut 23 has tapered lateral arms 24 received in the openings 6 of the toe sections 2 and holding the nut 23 in place in the guideway 4. The nut 23 is supplied with an upstanding lug 25 received in the 75 notches 26 of the toe sections 2. There is an oil duct 27 in the lug 25. The oil duct 27 cooperates with a threaded opening 28 in the nut 23. A screw 29 is threaded into the opening 28 of the nut 23. The screw 29 is 80 supplied at its rear end with a grip 30 whereby the screw may be rotated. The forward end of the screw 29 is connected by a ball and socket joint 31 with a rider 32, the rider being mounted to reciprocate in the 85 guideway 4 formed by the inclined longitudinal grooves 3. The rider 32 is so tapered at its forward end, as indicated at 33, that, cooperating with the lateral taper 5 in the guideway 4, it will separate the toe sections 90 2 when it is advanced by the screw 29, the screw advancing as it is rotated in the nut 23 wherein it is threaded.

The heel of the article is marked by the numeral 34 and is provided with an upstanding handle 35 whereby the heel may be manipulated. The heel 34 has a bore 36 terminating at its rear end in an enlargement 37 defining an internal shoulder 38. A connector 39, preferably a screw, is located in the bore 36 and in the enlargement 37. The forward end of the screw 39 extends into the notches 14 of the toe sections 2 and is mounted to swing on the connecting element 18. At its rear end, the screw 39 has an enlarged head 40 located in the part 37 of the bore 36. A compression spring 41 surrounds a portion of the screw 39. The rear end of the spring 41 abuts against the head 40 of the screw 39, and the forward end of the 105 110 screw 39 is located in the toe sections 2.

spring abuts against the shoulder 38. A washer 42 is mounted on the screw 39, slidably, and bears against the forward surface of the heel 34. A nut 43 is threaded on the screw 39 and engages the washer 42, the nut having projecting arms 44, whereby it may be rotated readily by hand.

In practical operation, the heel 34 may be swung upwardly and downwardly, by means 10 of the handle 35, during the insertion of the toe 1 in the shoe, and to enable the heel 34 to acquire a firm seat within the shoe, the connector or screw 39 swinging on the member 18. By rotating the nut 43 through the 15 instrumentality of the arms 44, the distance between the toe 1 and the heel 34 may be adjusted, and the device, therefore, may be adapted readily to shoes of different lengths, the compression spring 41 keeping the heel 34 under the control of the nut 43 as the connector or screw 39 slides for adjustment in the bore 36 of the heel 34.

By rotating the screw 29, the rider 32 may be advanced, as hereinbefore explained, to effect a separation of the toe sections 2 and to bring about a stretching of the shoe. The oil duct 27 in the lug 25 on the nut 23 enables the screw 29 to be lubricated. The arms 24 of the nut 23 hold the nut 23 25 against rotation, when the connectors or screw 39 is rotated and advanced or retracted in the member 23.

What is claimed is:—

1. In a device of the class described, a toe comprising laterally separable sections, means for connecting the said sections for lateral movement, means for expanding the said sections, a screw pivotally mounted on the toe, a heel slidable for adjustment on the screw, a nut threaded on the screw and co-operating with the inner end of the heel, and a compression spring on the screw, within the heel, one end of the spring being engaged with the screw, and the other end of the spring being engaged with the heel. 35 40 45

2. In a device of the class described, a toe comprising laterally separable sections, means for expanding the said sections, a connector pivoted to the toe, a heel mounted for sliding adjustment on the connector, longitudinally of the connector, mechanism under the control of an operator for sliding the heel on the connector in one direction, and spring means cooperating with the heel and with the connector to slide the heel on the connector in an opposite direction and to hold the heel yieldingly in engagement with said mechanism. 50 55

In testimony that we claim the foregoing as our own, we have hereto affixed our signatures. 60

ANDREW J. QUIST.
BERT A. MELLANDER.
